REFRIGERATOR SHELVING ARRANGEMENT

George C. Harbison, Erie, Pa., assignor to General Electric Company, a corporation of New York

Application February 19, 1954, Serial No. 411,463

1 Claim. (Cl. 312—311)

My invention relates to household refrigerating apparatus and more particularly to shelving arrangements for use in such apparatus.

In most household refrigerating apparatus, as for example household refrigerators and home freezers, a plurality of spaced horizontal shelves are provided in order to support the foodstuffs placed therein. The number of these shelves varies according to the size of the apparatus, but ordinarily in order to make efficient use of the refrigerated space available, the shelves must be placed so close together so that the upper shelf or shelves tend to block access to articles placed on the lower shelves. Heretofore various means have been advanced to alleviate this difficulty. For example, both sliding and rotating shelves have been provided. These in the main have been satisfactory from the standpoint of providing access to the articles stored upon the shelves. My invention, however, contemplates a new and improved shelf structure which utilizes stationary shelves yet provides ready access to the articles placed upon the shelves.

In carrying my invention into effect I provide household refrigerating apparatus having a refrigerated storage compartment, access to which is had through a vertically pivoted door. Within the storage compartment, I provide a shelving arrangement comprising a plurality of stepped horizontal stationary shelves mounted one above another with each shelf being less in depth than the shelf next below. This stepped shelf arrangement exposes to access articles placed on the lower shelf or shelves, or in other words, allows removal of articles from the lower shelves without blocking by the upper shelves. In order to utilize the storage space available because of the shortening of the upper shelves I also provide a plurality of stepped article supporting members mounted on the door. These supporting members extend into the compartment when the door is closed with each member being greater in depth than the member next below. At least a pair of these door members are complementary to different ones of the compartment storage shelves, i. e. on the same level as the shelves, and together with those shelves form storage levels extending substantially across the storage compartment. Thus the ready access to the articles placed on the storage shelves is accomplished without loss of storage space within the compartment.

The novel features which I believe to be characteristic of my invention are set forth with particularity in the appended claim. My invention itself, however, both as to its organization and method of operation may be best understood by reference to the following description taken in conjunction with the accompanying drawings in which:

Fig. 1 is a vertical sectional view of a refrigerator incorporating my new and improved shelving arrangement in one form thereof;

Fig. 2 is a perspective view of the door of the refrigerator shown in Fig. 1 illustrating the shelves mounted thereon in accordance with that form of my invention;

Fig. 3 is a fragmentary vertical sectional view of a

2

refrigerator incorporating another form of my new and improved shelving arrangement; and

Fig. 4 is a fragmentary perspective view of the door of the refrigerator shown in Fig. 3 illustrating the article supporting members mounted on the door in that form of my invention.

Referring now to Fig. 1, I have shown therein a refrigerator 1 in which a storage compartment 2 is defined by an inner liner or wall 3. The compartment 2 is thermally insulated from the surrounding room by means of insulation 4 positioned between liner 3 and the outer panel or wall 5 of the refrigerator; and it is refrigerated by means of an evaporator 6 which is fed with refrigerant by a condensing unit 7 positioned in a machinery compartment 8 at the base of the refrigerator. Access to the refrigerated or storage compartment 2 is had through a front opening 9 which is closed by means of a door 10. The door 10 is mounted on vertical pivots (not shown) so as to swing open and shut and has a gasket 11 mounted thereon for effectively sealing the opening 9 upon the door being closed. The door, like the main refrigerated cabinet, is formed of two spaced walls separated by insulating material, namely, inner and outer panels 12 and 13 and insulation 14. In order to provide additional storage space the inner panel 12 is provided with a large center recess 15.

Within the storage compartment 2 of the refrigerator 1 as defined by liner 3 and the inner panel 12 of the door, I have mounted one form of my new and improved shelving arrangement. However, it should be understood that the refrigerator 1 as thus far described is only illustrative of the numerous types of household refrigerating apparatus to which my shelving arrangement may be adapted.

In accordance with my invention for providing ready access to articles stored on refrigerator shelves without losing any of the available storage space within the refrigerator, I have mounted on the inner liner 3 of refrigerator 1 a plurality of spaced apart horizontal shelves 16, 17, and 18. The upper two shelves 16 and 17 are fixedly secured to liner 3 by any suitable means as for example brackets and screws (not shown). The lowermost shelf 18, however, is removable from the compartment, being supported by but not attached to a plurality of studs 19 secured to the inner liner. Further the removable shelf 18 serves as the mounting means for a sliding drawer 20 positioned thereunder, the side edges of shelf 18 being rolled under to form a bead which accommodates flanges provided at the top edges of the drawer 20. A handle 21 is provided on the drawer 20 for ease of operation.

It is, however, the configuration of the shelves rather than their manner of mounting or the members supported therefrom, which forms part of my invention. Specifically, it will be seen from the diagram that the shelves 16, 17, and 18 are stepped upwardly. That is, each shelf is less in depth than the one next below it. Thus the shelf 18 extends from the rear of the storage compartment practically to the door; shelf 17 extends only part way to the door, and shelf 16 extends even a shorter distance toward the door. As indicated by the articles shown in dotted lines in the diagram this stepped configuration of the shelves provides easy access to any food stuffs stored thereon. Since each shelf does not block access to the front portion of the shelf next below it, it is therefore much easier to remove articles from the lower shelf than it is when all the shelves are of the same length.

Just to provide these stepped shelves alone in a storage compartment would, however, waste much of the space therein. Therefore, in accordance with my invention, I have provided article supporting members on the door

which cooperate with the stepped shelves in the storage compartment so that substantially no storage space is lost as a result of the stepped shelf configuration. Thus, in the embodiment shown in Fig. 1 these article supporting members mounted on the door comprise the door shelves 22, 23, and 24. These door shelves, according to my invention, are stepped in the reverse direction to the shelves affixed to the cabinet. In other words each of the door shelves 22, 23, and 24 extends into the storage compartment somewhat further than the stepped shelf next below it. In other words each shelf is greater in depth than the shelf next below it.

To most effectively utilize the storage space available, at least a pair of these door members or shelves are complementary to different ones of the cabinet storage shelves and together therewith form storage levels extending substantially across the storage compartment. Thus for example, the uppermost door shelf 22 is complementary to the cabinet shelf 16 and the second door shelf 23 is complementary to the second cabinet shelf 17. Shelves 16 and 22 together form a storage level extending substantially across the storage space and shelves 17 and 23 together form a second level extending substantially across the storage space. In larger refrigerators wherein a taller storage space is provided, it would of course be possible to provide three or more steps of complementary cabinet and door shelves so as to make three or more storage levels extending substantially across the storage compartment. In fact, if desired, even in the illustrated refrigerator 1 a fourth cabinet shelf could be provided complementary to the lowermost door shelf 24 so as to provide a third storage level therein.

Thus through the provision of oppositely stepped shelves mounted in the cabinet and on the door I have provided a shelving arrangement which provides easy access to articles stored within the cabinet but yet does not waste any of the storage space. It should be noted incidentally that in the embodiment shown in Figs. 1 and 2 I have also provided an additional door shelf 25 above the uppermost door shelf 22 complementary with a cabinet shelf. The uppermost and shortest cabinet shelf 16 would ordinarily be used to support tall articles, as for example the quart soda and milk bottles illustrated by the dotted lines, so that it would not be desirable to have a door shelf extending over the shelf 16. But by the provision of a shelf of the same depth as the shelf 22 maximum utilization may be made of the space thereover without interfering with the space over the shelf 16. Thus in the embodiment shown in Fig. 1 the uppermost shelf 25 is substantially of the same size as the top stepped shelf 22. In fact, in the embodiment of Fig. 1 the shelves 22 and 25 are joined together by a plurality of strengthening posts 26. Further the wire grids 27 and 28 which form the article supporting members of the right hand portion of the shelf 25 may be removed so that tall articles such as soda bottles may be accommodated on the shelf 22.

It should also be noted that each of the door shelves is provided with an upstanding edge or other guard to prevent any articles stored thereon from falling off if the door should be slammed too hard. Although such edges or guards are not necessary to my invention, in practice it has been found desirable to provide them. Articles may be removed from the shelves 23, 24, and 25 simply by lifting them over their edges or guards. The front guard 29 of shelf 22 is, however, spring-biased to its position shown and may be pushed downwardly to replace articles on or remove them from shelf 22.

Referring now to Figs. 3 and 4 I have shown therein an alternate form of my invention. For convenience, identical elements in Figs. 3 and 4 to those in Figs. 1 and 2 are numbered the same in all the figures. As before and according to my invention, a plurality of stepped shelves are mounted within the storage compartment 2 with each shelf being greater in depth than the shelf

next below it. Thus here the cabinet is provided with the stepped shelves 30 and 31, the lower shelf 31 extending farther toward the door than the upper shelf 30. Beneath these shelves 30 and 31, which are fixedly secured to the inner liner 3 of the cabinet, are mounted a pair of removable shelves 32 and 33, these shelves resting respectively on a plurality of studs 34 and 35 secured to liner 3. Each of these removable shelves supports beneath it a sliding receptacle or pan, the side edges of the shelves being rolled under to provide a bead accommodating flanges on the top edges of the pans. Thus the upper removable member 32 supports the pan 36 and the lower removable member 33 the pan 37. Handles 38 and 39 are provided respectively on the pans in order to facilitate their operation. It should be noted, however, that if the removable member 32 and the pan 36 supported therefrom are removed completely from the storage compartment, the member 33 will comprise a third shelf in the stepped shelf configuration. In other words, with the member 32 and basket 36 removed, the member 33 will form a shelf next below the shelf 31 which is greater in depth than the shelf 31. As with the similar shelves shown in Figs. 1 and 2 these stepped cabinet shelves 30, 31, and 33 provide for greater accessibility to the contents stored on the lower shelf or shelves.

In order to make maximum utilization of the space resulting from the stepped configuration of the cabinet shelves the embodiment of my invention shown in Figs. 30, 2 and 3 also includes article supporting members mounted on the door which are complementary to at least a pair of the cabinet storage shelves. Thus I have provided complementary to the upper cabinet shelf 30 an article supporting member or shelf 40 and complementary to the second cabinet shelf 31 I have provided an article supporting member or basket 41. The upper article supporting member 40 extends further into storage compartment 2 than the lower supporting member or basket 41 or in other words the upper door member is greater in depth than the member next below it. The upper door member 40 and the upper cabinet shelf 30 together form one storage level extending substantially across the storage compartment and the bottom of the lower door member 41 and the second cabinet shelf 31 together provide a second storage level extending substantially across the compartment.

The upper door member or shelf 40 is firmly affixed to the inner panel 12 of the door whereas the lower member or basket 41 merely rests against the door and is movable therefrom. Specifically the basket 41 is supported from a third door supporting member or shelf 42 affixed to the door above the shelf 40. This uppermost door shelf 42 is provided in order to utilize the rather large storage space remaining above the top stepped member 40. The shelf 42 does not extend any further into the storage compartment than the shelf 40 in order that the cabinet shelf 30 may be utilized to store tall articles such as bottles. Moreover the right hand grids 43 and 44 of shelf 42 may be removed to permit the storage of tall articles on the shelf 40. Posts 45 run between shelves 40 and 42 in order to strengthen both. The basket 41 is supported from the shelf 42 by means of a plurality of pivotally mounted links. Thus the one end of the basket is attached to one side of the shelf by links 46 and 47 while the other end of the basket is attached to the other side of the shelf 42 by links 48 and 49. These links 46-49 are pivoted at their upper ends in recesses provided in the sides of shelf 42 and at their lower ends are pivoted in journals provided on the base of the basket 41, the journals 50 and 51 for accommodating the lower ends of links 46 and 47 being shown.

As shown in Fig. 4 the action of these links allows the basket or supporting member 41 to be swung out from underneath the member or shelf 40, a handle 52 being provided on the basket to facilitate this procedure. Once

the basket or receptacle 52 has cleared the shelf 40, the lid 53 thereof may be lifted so as to permit access to the contents of the basket. Once the desired articles have been removed from or placed in the basket 41, it may then be swung back into its normal position against the inner panel 12 of the door as illustrated in Fig. 3. Any suitable catch, as for example a spring catch, may be utilized to retain the basket in its normal or retracted position. The swinging basket construction is of course advantageous in that it provides a large storage space close under the next higher shelf, which space is nonetheless easily accessible due to the movability of the basket.

Summing up, it may be seen that through my invention I have provided a new and improved shelving arrangement which permits ready access to the contents of any shelf but yet utilizes the available storage space within the refrigerator very effectively. Through the provision of stepped shelves within the main storage space, no shelf blocks off the shelf next beneath it, and the complementary article supporting members on the door effectively utilize the space remaining as a result of this stepped configuration. As shown by the two illustrated embodiments, the reverse stepped supporting members mounted on the door may take various forms. Just so long as they complement the main cabinet shelves so as to form storage levels extending substantially across the storage compartment no appreciable amount of space within the compartment can be wasted.

From a consideration of the above, it will be obvious to those skilled in the art that various changes and modifications may be made in the disclosed structure without departing from my invention. Therefore, while in accordance with the patent statutes I have described what at present are considered to be the preferred embodiments of my invention, it will be understood that in the appended claim I intend to cover all such changes and modifications as fall within the true spirit and scope of my invention.

What I claim as new and desire to secure by Letters Patent of the United States is:

5 In refrigerating apparatus having a refrigerated storage compartment and a door providing access to said compartment, a shelving arrangement comprising a plurality of horizontal storage shelves mounted in said compartment with each shelf being less in depth than the shelf next below thereby to expose to access articles placed on the lower shelf, and a storage receptacle and at least one 10 horizontal door shelf mounted on said door and extending into said storage compartment with said receptacle being positioned beneath said one door shelf and being less in depth than said one shelf, said receptacle having movable mounting means including a plurality of pivoted links supporting said receptacle from said one door shelf and effective to swing said receptacle out from beneath said shelf thereby to provide access to said receptacle, and said receptacle and said one shelf being complementary to different ones of said storage shelves and together therewith forming storage levels extending substantially across said storage compartment, whereby the ready access to the articles placed on said storage shelves is accomplished without loss of storage space within said compartment.
